(57) **CLAIM**

The ornamental design for a motorcycle wind deflector accessory support, as shown and described.

DESCRIPTION

FIG. 1 is a front perspective view of a first embodiment of a motorcycle wind deflector accessory support;

FIG. 2 is a front elevational view of the motorcycle wind deflector accessory support of FIG. 1;

FIG. 3 is a rear elevational view of the motorcycle wind deflector accessory support of FIG. 1;

FIG. 4 is a left side elevational view of the motorcycle wind deflector accessory support of FIG. 1;

FIG. 5 is a right side elevational view of the motorcycle wind deflector accessory support of FIG. 1;

FIG. 6 is a top plan view of the motorcycle wind deflector accessory support of FIG. 1;

FIG. 7 is a bottom plan view of the motorcycle wind deflector accessory support of FIG. 1;

FIG. 8 is a rear perspective view of the motorcycle wind deflector accessory support of FIG. 1 showing environment that forms no part of the claimed design in dot-dash lines;

FIG. 9 is a front perspective view of a second embodiment of a motorcycle wind deflector accessory support;

FIG. 10 is a front elevational view of the motorcycle wind deflector accessory support of FIG. 9;

FIG. 11 is a rear elevational view of the motorcycle wind deflector accessory support of FIG. 9;

FIG. 12 is a left side elevational view of the motorcycle wind deflector accessory support of FIG. 9;

FIG. 13 is a right side elevational view of the motorcycle wind deflector accessory support of FIG. 9;

FIG. 14 is a top plan view of the motorcycle wind deflector accessory support of FIG. 9;

FIG. 15 is a bottom plan view of the motorcycle wind deflector accessory support of FIG. 9; and,

FIG. 16 is a rear perspective view of the motorcycle wind deflector accessory support of FIG. 9 showing environment that forms no part of the claimed design in dot-dash lines.
